(57) **CLAIM**

We claim the ornamental design for the shoe sole, as shown and described.

DESCRIPTION

FIG. 1 is a front perspective view of the shoe sole embodying our design;

FIG. 2 is a side elevational view of the shoe sole shown in FIG. 1;

FIG. 3 is the other side elevational view of the shoe sole shown in FIG. 1;

FIG. 4 is the front elevational view of the shoe sole shown in FIG. 1;

FIG. 5 is a rear elevational view of the shoe sole shown in FIG. 1; and,

FIG. 6 is a top plan view of the shoe sole shown in FIG. 1. The broken lines show the complete shoe sole and form no part of the design to be patented.
